MICROWAVE ANTENNA

Nathaniel I. Korman, Merchantville, N. J., assignor to Radio Corporation of America, a corporation of Delaware

Application February 17, 1950, Serial No. 144,629

11 Claims. (Cl. 250—33)

1

The present invention relates to microwave antennas.

It is frequently desirable in the broadcast of radio waves to use an antenna which has a radiation pattern omnidirectional in the horizontal plane and with high directivity in the vertical plane. With such an antenna large broadcast areas may be serviced by the microwave radiation therefrom. Similar antennas are useful as radar beacons or the like and also may find employment in television broadcasting. Such antennas have been proposed, for example, in my co-pending application, Serial No. 1634, filed January 10, 1948, entitled "An Antenna for Microwave Beacons" which, however, radiate electromagnetic energy in which the electric vector is horizontally polarized. It is often desirable in certain applications to have the radiation from such antennas circularly polarized, because circular polarization has numerous advantages, as already known to the art.

It is an object of the present invention to provide a novel antenna having a radiation pattern which has high directivity in the planes through a predetermined axis and which is substantially omnidirectional in a plane normal to the axis.

A more particular object of the invention is to provide an antenna having a circularly polarized radiation pattern substantially omnidirectional in the horizontal plane and of high directivity in the vertical plane.

A still further object of the invention is to provide an antenna having a circularly polarized radiation pattern omnidirectional in a plane normal to said axis and of high directivity in planes through a predetermined axis.

These and other objects, advantages and novel features of the invention will be more apparent from the following description when taken in connection with the accompanying drawing in which like reference numerals refer to like parts and in which:

Fig. 1 is a schematic face view of one embodiment of the invention using one set of parallel plates normal to the predetermined axis as a focusing element and another set as a polarizing element;

Fig. 2 is a schematic cross sectional view of the embodiment of Fig. 1 taken through the predetermined axis;

Fig. 3 is a schematic cross sectional view of another embodiment of the invention through the axis thereof and in which embodiment a set of substantially parallel plates in radial planes are employed as a focusing element;

2

Fig. 4 is a schematic plan view of the embodiment of Fig. 3;

Fig. 5 is a schematic cross sectional view through the axis thereof of an embodiment of the invention in which there are two sets of substantially parallel plates each set employed as a focusing element;

Fig. 6 is a schematic cross-sectional view of an embodiment as shown in Fig. 5, but with inner and outer plates interchanged in position from that of Fig. 5.

The foregoing objects and others are achieved according to the invention by utilizing a central radiator or receptor with a radiation pattern substantially omnidirectional or non-directional about a predetermined axis. Two sets of substantially parallel metallic plates surround the radiator or receptor, one set within the other, at least one of the sets comprising a metallic lens element to give the energy high directivity in planes through said axis. The omnidirectional characteristic of the radiation is preserved by maintaining substantial symmetry about the axis. It is clear that if the axis is chosen to be a vertical axis, the radiation pattern will have high directivity in the vertical plane and will be omnidirectional in the horizontal plane. Circular polarization is achieved by various means depending upon whether the radiator or receptor has characteristics of horizontal polarization, vertical polarization, or circular polarization. In these respective circumstances, the focusing set of elements may be disposed in horizontal planes, radial planes, or in both planes, in the latter case both sets of parallel metallic plates operating as lenses. It will be understood throughout the description and claims that an antenna may operate either to radiate or to receive electromagnetic energy. The antenna has a reception pattern which is characterized by the radiation pattern.

Accordingly, it will be understood further that although the description may be directed to the antenna as a radiator, the antenna is equally useful for reception. It also simplifies the description, and an understanding thereof, to follow the usual convention adopted herein, regarding polarization, namely, that the direction of polarization is understood as that of the electric vector of the energy.

Referring now more particularly to Figs. 1 and 2, which are respectively a face view and an axial cross sectional view of the embodiment of the invention, a transmission line 10 is connected to a circular waveguide portion 12, having vertical slots 14 which may be excited to radiate horizontally polarized energy, when the waveguide

12 is excited in the $TE_{0,1}$ mode. As well understood in the art, if there are a sufficient number of circumferentially equally spaced slots 14, the slots having an axial length greater than their width, the radiation pattern of the waveguide radiator portion 12 is substantially omnidirectional in character. In practice, four slots equally spaced circumferentially are usually sufficient. The slotted waveguide 12 is merely an exemplification of any one of various radiators having such omnidirectional radiation characteristics.

10 A set of substantially parallel metallic plates 16 surround the waveguide radiator portion 12 substantially in planes normal to the predetermined axis 8 about which the omnidirectional radiation is directed. The plates 16 have varying inner and outer diameters, and those near the top and bottom of the structure, as apparent from Fig. 2, have a greater radial depth than those near the center of the structure. The horizontally polarized energy passing between these plates 16 travels at a phase velocity greater than the velocity of light whereby the plates 16 act as a lens element giving the energy high directivity in planes normal to the axis 8. The lens element illustrated here is by way of exemplification. There are other lens elements of parallel metallic plates suitable for the purpose, for example, those respectively shown in Figs. 1-5 of my co-pending application, Serial No. 1634, filed January 10, 1948, entitled "An Antenna for Microwave Beacons."

15 The lens element plates 16 are substantially entirely surrounded by a second set of substantially parallel metallic plates 18 which, however, lie in planes inclined substantially at 45° angles to the axis 8. It will be understood that it may not be possible to arrange the plates 18 to be parallel in a mathematically perfect sense although they will be parallel substantially and in a descriptive sense as viewed by an observer from a point a considerable distance from the antenna in a central plane normal to the axis 8.

20 Thus energy directed from the outer edge of the plates 16 with the electric vector horizontal strikes the inner edge of the space between the plates 18. The plates 18 are inclined at an angle of 45° to the axis 8 and the electric vector of the incident energy. Considering the energy now as being resolved into two portions, that polarized normal to the plates 18 and that polarized parallel to the plates 18, it is apparent that a phase shift between the two is readily secured depending upon the radial depth of the plates 18 and the separation between them. This phase shift between the resolved energy portions may be made substantially 90° , whereupon the energy emitted from the spaces between the plates 18 is directed outwardly as circularly polarized energy. The sense of rotation of the circular polarization depends upon the sense of inclination of the plates 18, being in one sense of rotation with the plates 18 inclined in one sense with respect to the axis 8 and being in a countersense of rotation with the plates 18 inclined in the other sense with respect to the axis 8. The energy from the antenna as a whole is circularly polarized, is substantially omnidirectional about the axis 8, and has high directivity in radial planes through the axis 8.

25 Referring now to Figs. 3 and 4, respectively cross sectional and plan views of another embodiment of the invention, a coaxial line section 20 has a circumferential slot 22 whereby the section 20 radiates vertically polarized energy.

30 The section 20 is fed by a transmission line 21. A set of plates 24 are arranged in radial planes about the axis 8 and symmetrically surround the radiator coaxial line section 20. The radial depth of the plates 24, considering their number, is made sufficiently short with respect to the distance of the plates from the axis 8 that the plates may be considered to be substantially parallel even though they are actually in radial planes. It is obviously also possible to thicken the outer edges of the plates 24 to be wedge-shaped whereby adjacent surfaces of adjacent plates are parallel, but I prefer for reasons of simplicity to use planar plates, as shown in Fig. 4. Surrounding the plates 24 are arranged a set of substantially parallel metallic plates 18 which may be the same as the plates 18 of Fig. 1.

35 In the operation of the arrangement of Fig. 4 the axis 8 may be assumed vertical. The vertically polarized energy from radiating line section 20 travels for a longer time at the same phase velocity between the upper and lower ends of plates 24 than it does between the central portions thereof, whereby the energy radiated there-through is given a high directivity in planes through the axis 8 by suitable design of the contours of the plates 24. The planes of the plates 18 are inclined at an angle of 45° to the vertical whereby as before a suitable phase shift of a portion of the energy results in circular polarization as it is emitted from the antenna. Energy radiated from the antenna of Fig. 4 is circularly polarized and has high directivity in any plane through the axis 8.

40 Referring now more particularly to Fig. 5 which is a cross sectional view of still another embodiment of the invention, a transmission line 10 feeds a radiator 26 having circularly polarized characteristics and having a radiation pattern substantially omnidirectional with respect to a predetermined axis 19. The radiator 26 may comprise a section of coaxial transmission line having circular apertures 27 located centrally of the antenna. A set of metallic plates 28 surrounds the axis 19 and radiator 26. The plates 28 are arranged substantially symmetrically with respect to the axis 19. These plates may be the same as the plates 24 of Figs. 3 and 4 except that the radially inner and outer contours may be different. A second set of substantially parallel metallic plates 30 surrounds the first set and these plates 30 may be the same as the plates 16 of Figs. 1 and 2, except that they may have different inner and outer contours. In operation, the circularly polarized energy from radiator 26 has one component thereof focused by the plates 26 and the other component normal thereto focused by the plates 28, whereby the circular polarization may be maintained, provided that the energy emitted at any point on radiator 26 as it travels radially outward has both the vertical and horizontal component shifted in phase by substantially the same amount in its travel between the plates 26 and 28 respectively. Simple calculation by those skilled in the art yields the necessary design relationship. The inner plates of Fig. 5 may be interchanged in position with the outer, as illustrated for example in Fig. 6, wherein the plates 30 and 28 have had their positions interchanged from those shown in Fig. 5.

45 In view of the foregoing description it will be apparent that there is disclosed a novel and highly useful antenna having circular polarization characteristics together with all the advantages thereof and having an omnidirectional ra-

diation pattern with respect to a predetermined axis and having high directivity in radial planes through said axis.

What I claim is:

1. An antenna comprising a central radiator or receptor having a radiation pattern substantially non-directional about a predetermined axis, a first set of substantially parallel metallic plates surrounding said radiator or receptor, and a second set of substantially parallel metallic plates surrounding said first set, both the said sets of plates being arranged substantially symmetrically about said axis whereby the antenna radiation pattern is substantially omnidirectional about said axis, at least one of said sets of plates being arranged as a metallic lens element to cause the radiation pattern from said antenna to have high directivity in any plane through said axis.

2. The antenna claimed in claim 1, said first set of plates lying in planes normal to said axis.

3. The antenna claimed in claim 1, said first set of plates lying in planes normal to said axis and being arranged as said lens element, said second set of plates lying substantially in planes inclined each substantially at an angle of 45° with said axis, whereby circular polarization of radiated energy is realized.

4. The antenna claimed in claim 1, said first set of plates lying substantially in radial planes through said axis and being arranged as said lens element.

5. The antenna claimed in claim 1, said first set of plates lying in radial planes through said axis and being arranged as said lens element, said second set of plates lying substantially in planes inclined each substantially at an angle of 45° with said axis, whereby circular polarization of radiated energy is realized.

6. The antenna claimed in claim 1, said second set of plates lying substantially in radial planes through said axis, and being arranged as a second lens element, said radiator or receptor having circular polarization characteristics.

7. The antenna claimed in claim 1, said second

set of plates lying substantially in planes inclined each substantially at an angle of 45° with said axis and being all of the same radial depth.

8. The antenna claimed in claim 1, said second set of plates lying in planes normal to said axis.

9. The antenna claimed in claim 1, said second set of plates lying in planes normal to said axis and having different radial depths to serve as said metallic lens element.

10. The antenna claimed in claim 1, said first set of plates being arranged as said lens element, said second set of plates lying in planes normal to said axis and having differing radial depths thereby to be arranged as a second lens element to enhance energy focus in planes through said axis, said radiator or receptor having circular polarization characteristics.

11. An antenna comprising a central radiator or receptor having a radiation pattern substantially non-directional about a predetermined axis, a first set of substantially parallel metallic plates surrounding said radiator or receptor, and a second set of substantially parallel metallic plates surrounding said radiator or receptor, the plates of one of said sets being disposed normally to those of the other, each of said sets of plates being arranged symmetrically about said axis, whereby the radiation pattern is substantially omnidirectional about said axis, at least one of said sets of plates being arranged as a metallic lens element to cause the radiation pattern from said antenna to have high directivity in any plane through said axis.
